Charles L. Smith

By Clarence O'Brien.

Attorney

UNITED STATES PATENT OFFICE.

CHARLES L. SMITH, OF PONCA, NEBRASKA.

SCYTHE.

Application filed October 9, 1926. Serial No. 140,590.

This invention relates to improvements in scythes, and it has more particular reference to novel means for connecting the blade to the snathe in a manner to permit the blade to be rotated around the snathe or to be adjusted angularly with respect to the same in order to make convenient the handling the scythe.

The present invention is directed to an improvement upon Patent No. 1,247,461 granted to me on November 20, 1917.

In the patent referred to, a socket is provided including a cap to fit upon the end of the snathe, this cap being formed with a toothed projection having a retaining bolt associated therewith.

The blade has a special heel construction which cooperates with said toothed part and it is provided with an elongated slot through 20 which the clamping bolt extends and further provided with teeth adapted to be locked upon the first named teeth.

The socket is of split form and a clamping bolt is associated therewith for permitting it to be rotated about the snathe and clamped in any desired position.

The present structure has been designed to improve upon the patented structure by rearranging the cooperating retaining teeth, 30 by providing a separate pivotal connection between the blade and the socket member, and to provide more efficient clamping means for the socket.

The specific details forming the alleged improvement will become more readily apparent from the following description and drawings.

In the drawings forming a part of this application and in which like numerals are employed to designate like parts throughout the same:

Figure 1 is a rear elevational view of the complete structure.

Fig. 2 is an elevational view taken at approximate right angles and looking at the end of the clamping means and blade, etc.

Fig. 3 is a detail elevation of the socket member, and

Fig. 4 is a detail view of the blade retaining means.

In the drawing, the reference character 1 designates the snathe, which has an upper tapered end fitting snugly into the cap portion 2 of the improved socket member. Depending from one side of this cap is a trans-

versely curved apron 3, which is provided at its lower end with outstanding apertured ears 4. The screw threaded ends of a pair of retaining bolts 5 extend through the ears and these bolts are carried on a U-shaped retaining strap 6 having a central outwardly pressed portion 7 fitting over a depending finger 8 on the rear half of the cap 2.

This serves to hold the cap member in place and to permit it to be turned around the snathe to any desired position. Formed between the ears 4 on the lower portion of the apron 3 is a gear segment 9, and at the center of this is a hole 10 for passage of a bolt 11. As shown in Fig. 2, a polygonal socket is 70 formed in the inner side of the gear segment as shown and the head of the bolt is located in this socket as indicated at 12.

Extending upwardly from the gear segment is a reinforcing rib 13 connected with 75 a circular head 14 having a correspondingly shaped socket or recess 15 formed therein.

The blade is represented by the reference character 16 and the same includes a special heel formation indicated at 17. On the inner face of this is a thickened portion 18 terminating at its bottom in a gear sector 19 cooperating with the gear segment 9. This portion 19 is provided with an elongated arcuate slot 20 for registry with the bolt hole 85 10 and the aforesaid bolt extends through this and carries a retaining nut 21 as shown in Fig. 2. At the upper end of the part 18 is a circular projection 22 which fits into the recess 15.

A bolt 23 has its head resting upon a seat 24 and has its shank extending through openings in the head 14 and projection 22. The clamping nut 25 thereon is arranged in a depression 26 formed in the outer side. The 95 reference character 26 in Fig. 4 represents a beveled surface and the reference character 27 represents a reinforcing rib which is cut away as at 28 to accommodate the adjacent rounded periphery of the special head 14.

With the arrangement specified, it will be seen that a positive pivotal connection is provided by the means 14, 22, and bolt 23. Thus, by simply loosening the nut 21 on the bolt 11, the gear teeth 9 and 19 may be ratcheted over 105 each other to permit the angularity of the blade being varied with respect to the snathe. Independent rotary adjustment of the socket member is permitted by the aforesaid clamping means 5.

From the description and drawing, it will be seen that the improvement is characterized by exceptional strength, simplicity of construction, inexpensiveness of manufacture, and efficiency in operation and use. It is believed that by considering the description in connection with the drawings, a clear understanding of the invention will be had. Therefore, a more lengthy description is thought unnecessary.

Having thus described my invention, what I claim as new is:—

1. In a structure of the class described, a socket member including a cap, adapted to be fitted upon the end of a snathe, a head projecting above the cap and including a circular recess, a blade having a lateral projection fitting rotatably into said recess, a bolt pass-

ing through said head, projection and blade, a gear segment carried by the socket member, 20 a gear sector carried by the blade and co-operable with the gear segment, and a clamping bolt associated therewith.

2. As a new product of manufacture, a cap, a depending arcuate apron, outstanding apertured ears carried by the lower end of the apron, a gear segment arranged between said ears, a recessed head carried by and extending above the cap, a finger depending from the rear half of the cap, a retaining strap 30 cooperable with said finger, and bolts carried by said strap and extending thru the apertures in said ears.

In testimony whereof I affix my signature.

CHARLES L. SMITH.
